UNITED STATES PATENT OFFICE

166,050

MASSAGER

Oscar N. Sandholm, Denver, Colo.

Application September 15, 1951, Serial No. 16,646

Term of patent 14 years

(Cl. D83—1)

To all whom it may concern:

Be it known that I, Oscar N. Sandholm, a citizen of the United States of America, residing at Denver, in the county of Denver and State of Colorado, have invented a new, original, and ornamental Design for a Massager of which the following is a specification, reference being had to the accompanying drawing, forming a part hereof.

Fig. 1 is a top view of a massager showing my new design;

Fig. 2 is a side view thereof;

Fig. 3 is a bottom view thereof; and

Fig. 4 is an end view thereof.

I claim:

The ornamental design for a massager, as shown.

OSCAR N. SANDHOLM.
